UNITED STATES PATENT OFFICE.

EWAN CAMERON, OF BROOKLYN, NEW YORK, ASSIGNOR TO ALAN J. CAMERON, OF BROOKLYN, NEW YORK.

SWITCH FOR TROLLEYS.

No. 885,000.

Specification of Letters Patent.

Patented April 14, 1908.

Application filed April 25, 1907. Serial No. 370,152.

To all whom it may concern:

Be it known that I, EWAN CAMERON, a citizen of the United States, and a resident of the borough of Brooklyn, county of Kings, 5 State of New York, have invented certain new and useful Improvements in Switches for Trolleys, of which the following is a specification.

The object I have in view is the production of a switch for overhead trolleys, which 10 will possess great stability and strength, which may be easily operated and will be self-locking, and which will be operated with ease and certainty.

15 A further object that I have is producing a switch in which the curve will be even and without abrupt turns.

Further objects are in providing a switch in which there will be an inability of the trolley coming off the track at the switch.

Other objects will more fully appear from the following specification and accompanying drawings, taken together or separately.

I attain these objects by the mechanism 25 illustrated in the accompanying drawings, in which

Figure 1 is a plan view of a track showing my switch in position. Fig. 2 is a side elevation of the same. Fig. 3 is an enlarged section on the line *a—a* of Fig. 1. Fig. 4 is an enlarged top view of the switch shifting mechanism. Fig. 5 is a sectional view of the same on the line *c—c* of Fig. 4; and Fig. 6 is a section on the line *b—b* of Fig. 4.

35 In all the views like parts are designated by the same reference characters.

My invention is used in connection with switches with tracks for overhead trolleys. These tracks are mounted upon supports 40 that depend from a ceiling or other structure.

In illustrating the embodiment of my invention, I show a switch which comprises a moving member or track 1 and fixed members or tracks 2 and 3. The number of fixed 45 members may be increased, as is obvious. The fixed and moving members depend from a fixed support by means of hangers 4 and 5. The ends of the fixed members or tracks 2 and 3 terminate adjacent to the end of the 50 moving track or member 1 so that the latter may be swung to form a continuous way over the track 2 or over the track 3 as desired.

One feature in my invention consists in

making the moving member of the switch so that it may be thrown without any abrupt 55 change in direction in the track. This I attain by adequately supporting its free end upon the fixed members 2 and 3 or upon the support 4, or upon means supported by the support 4, and sustaining it intermediate its 60 ends by the hanger 5, at a sufficient distance away from its free end, so that the moving member may be flexed and brought into alignment with either of the tracks 2 and 3. In order to get a still better support for the moving member I may arrange the hanger 5 nearer to the free end of the moving member, but provide such hanger with means to permit the moving member to pivot upon it. One way of attaining this end is to provide a 70 hanger 5 with a pivot 6 so that the moving member may be turned. A satisfactory support is also disclosed in my co-pending application for patent, filed April 25, 1907, Serial No. 370,153. The additional supports for 75 the moving member (not shown) may have, or not, as desired, pivots so as to permit the more ready flexing of the moving member by increasing its length between rigid supports.

The free end of the moving rail is provided 80 with an extension or shoe 7, which rests upon and is supported by a plate 8, which is carried upon the free ends of the fixed rails 2 and 3. This plate 8 serves the triple purpose of a tie for securing together and in fixed 85 alignement the fixed rails, as a support or slide for the shoe, so that the weight of the free end of the moving rail is taken up, and as supports for the bearings of the shaft 9, which actuates the mechanism for throwing 90 the switch. To support the shaft bearings 9, the plate is made to extend a sufficient distance beyond the fixed rails 2 and 3 and is bent upward, forming extensions 10. The shaft 9 carries a screw thread 11 so that it 95 constitutes a screw. This screw engages with a nut 12, which connects to the shoe 7, and by means of which the switch is thrown. Connections between the nut and the shoe are best made as illustrated and consist in 100 making the nut with a peripheral groove 13, which rests within a notch 14 formed in the vertical web of the shoe 7; the nut is made rectangular and the notch is made of a similar shape so that the nut will not turn within 105 the notch. The shoe is best made of a por-

tion of T shape steel as shown in Fig. 6. The shaft 9 extends beyond one of its bearings a sufficient distance to carry a sprocket wheel 15, around which the chain 16 passes. The bight of the chain extends downward a suitable distance to enable it to be grasped by a person on the ground. By means of this chain the sprocket wheel and shaft 9 may be rotated moving the nut and shoe, and with 10 it the free end of the moving rail 1 from one side to the other, so as to throw the switch, and form a continuous track in alinement with either of the fixed rails 2 or 3. A bracket 17 may be provided for preventing 15 the chain from coming off the sprocket wheel. The length of the plate 8 and the inside distance between the extensions 10 in connection with the width of the shoe 7 should be such that when the switch is thrown from 20 one side to the other the extreme distance the shoe will come in contact with the extension, and serve as a means of indicating to the operator that the switch has been completely thrown. This arrangement, of course, 25 would be used only in connection with a three or more point switch at the extreme points of throw. In connection with the 2-point switch, as illustrated, it serves as an effective and positive means to prevent the 30 operator throwing the switch too far and at the same time indicating to him that the switch has been completely thrown. In other switches with which I am familiar no means is provided for accomplishing this end. 35 Another portion of my invention consists in providing means for preventing a trolley running off one or the other of the fixed rails when the switch is open for that rail. I accomplish this by providing the moving member of the switch with means such as the 40 arms 18—19, which are supported upon the free end of the moving rail and extend across the free ends of the fixed rails in such a position that they will engage with the trolley on 45 the open track. These plates are best clamped upon the top of the moving member between it and the shoe 7. The two arms may be formed integrally with a supporting 50 plate 20. The arms are bent downward as shown in Fig. 3 so that they will extend across the path of the fixed members 2 and 3, and so arranged that when the moving member is in line with the fixed member 2 the arm 18 will extend across the end of the fixed 55 member 3 in such position that the trolley 21 will be intercepted and will be prevented from running off from the free end of the fixed rail. When the switch is thrown so that the moving member is in line with the 60 fixed rail 3, then the arm 19 will be in the same position and serve the same purpose in regards to the fixed rail 2.

From the above description it will be seen

that my switch can be moved to operate with a load on the moving element. It will 65 also be seen that in my invention the switch cannot by accident be opened, but would be locked in any position in which it is moved. It will also be seen that my switch is absolutely positive in its motion and does not depend upon rollers or wheels.

In accordance with the provisions of the patent statutes, I have described the principle of my invention, together with the apparatus which I now consider to represent the 75 best embodiment thereof; but I desire to have it understood that the apparatus shown is merely illustrative and that the invention can be carried out in other ways.

Having now particularly described the 80 nature of my invention, and in what manner the same is to be performed, what I claim and desire to secure by Letters Patent is:

1. A switch for an overhead trolley, which comprises a section of track, the free end of 85 which is mounted upon a slide and supported thereby, and an intermediate pivotal support which allows the track when flexed to pivot upon the support.

2. A switch for an overhead trolley, which 90 comprises a section of track, the free end of which is mounted upon a support, and an intermediate pivotal support which allows the track when flexed to pivot upon the support.

3. A switch for overhead trolleys having a 95 depending support for the rails, a moving member and a screw for moving such member there being a nut on the moving member, with which the screw directly engages.

4. A switch for overhead trolleys having in combination, a plurality of fixed rails and a moving rail, with means for moving the rail across the ends of the fixed rails, and a bar mounted upon and carried by the moving rail and extending across the ends of the fixed rails to provide a means for closing the ends of such rails.

5. A switch for an overhead trolley, which 110 comprises the moving member and fixed members, throwing mechanism and a plate, the moving member having a shoe and the fixed members being connected together by the plate upon which the shoe slides, the said plate supporting the throwing mechanism.

6. A switch for an overhead trolley, which 115 comprises the moving member and fixed members, the moving member having a shoe and the fixed members being connected together by a plate upon which the shoe slides, the said plate having upturned extremities, there being a screw carried by such upturned extremities and engaging with a nut for throwing the switch.

7. The combination, with an overhead 125 trolley, of a section of track, fixed at one end

and free to move at the other by flexion, as distinguished from pivoting, and a plurality of sections of track with their free ends fixed and abutting the free end of the first section 5 of track, with means for flexing the first section of track to bring its free end opposite the ends of the fixed sections of track so that the trolley may pass from the movable sec-

tion of track to any one of the fixed sections, or vice versa. 10

This specification signed and witnessed this 22nd day of April, 1907.

EWAN CAMERON.
